UNITED STATES PATENT OFFICE.

JAMES WILLIAM CAIN AND WILLIAM A. SKINNER, OF ORLANDO, FLORIDA.

DESIGN FOR A FLIER FOR AERIAL TOPS.

SPECIFICATION forming part of Design No. 24,692, dated September 24, 1895.

Application filed August 21, 1895. Serial No. 560,059. Term of patent 7 years.

To all whom it may concern:

Be it known that we, JAMES WILLIAM CAIN and WILLIAM A. SKINNER, citizens of the United States, residing at Orlando, in the county of Orange and State of Florida, have invented a certain new and useful Design for Flier for Aerial Tops; and we do declare the following to be a full, clear, and exact description of the invention, such as will enable others skilled in the art to which it appertains to make and use the same, reference being had to the accompanying drawings, which form a part of this specification.

This invention relates to a certain new and useful design for a "flier" for aerial tops.

The invention is clearly illustrated in the accompanying drawings, which form a part of this specification, and in which—

Figure 1 is a perspective view of a flier embodying our design. Fig. 2 is a section upon the line $x-x$ of Fig. 1.

Reference being had to the accompanying drawings, the essential features of our design comprise a central disk having lateral arms, four in number, radiating from the said disk

upon lines drawn at right angles through the center of the disk. These arms are each provided at their outer ends with blades which are concavo-convex in form, the inner edges of the several blades coinciding with the circumference of a circle described about the disk-center. The blades are uniform in size and shape, each being wider at one of its ends than at the other and the several blades being spirally disposed around the disk with the smaller or narrow ends of the blades inclined downward and extended in the same general curved or spiral line around the disk.

Having thus described our design, what we claim as new, and desire to secure by Letters Patent, is—

The design for a flier for aerial tops, substantially as shown and described.

In testimony whereof we affix our signatures in presence of two witnesses.

JAMES WILLIAM CAIN.
WILLIAM A. SKINNER.
